UNITED STATES PATENT OFFICE.

SPENCER K. BROWN, OF SYRACUSE, NEW YORK.

VALVE GEAR.

Application filed October 29, 1919, Serial No. 334,219.

To all whom it may concern:-

Be it known that I, SPENCER K. BROWN, a citizen of the United States, residing at Syracuse, in the county of Onondaga and 5 State of New York, have invented a certain new and useful Valve Gear, of which the following is a specification.

This invention relates to a valve mechanism, and especially a valve mechanism applicable for use in surface finishing machines of the type set forth in my Patent No. 1,276,167, issued August 20, 1918, and has for its object a particularly simple and efficient synchronizing means for the valve mechanism which is especially simple in construction, and highly efficient and durable in use and further which cannot get out of order.

The invention consists in the combinations and constructions hereinafter set forth and claimed.

In describing this invention reference is had to the accompanying drawings in which like characters designate corresponding parts in all the views.

25 Figure 1 is a side elevation, partly in section, of a surface finishing machine embodying my invention.

Figure 2 is a plan view thereof.

30 Figure 3 is a longitudinal sectional view on line 3—3, Fig. 1.

Figure 4 is a vertical sectional view on line 4—4, Fig. 1.

35 Figure 5 is an end elevation of parts seen in Fig. 2, the gear case cover being removed.

Figure 6 is an enlarged sectional view, partly in elevation on lines 6—6, Fig. 3.

Figure 7 is a sectional view on line 7—7, Fig. 1.

40 Figure 8 is a plan view of parts seen in Fig. 7.

Figure 9 is a plan view of parts seen in Fig. 7, the top plate being removed.

Figure 10 is a sectional view on line 10—10, Fig. 7.

Figure 11 is a face view looking to the right in Fig. 7.

Figure 12 is an enlarged sectional view through the operating valve.

50 Figure 13 is a detail view of the valve piece shown in Fig. 12.

This invention comprises oppositely movable reciprocating members, means as a valve for controlling the actuation of said members, the valve including a shiftable part, the members having means for alternately en-

gaging said part to shift the same and synchronizing mechanism operated by the reciprocating parts for timing the operation of said part.

The machine in which my invention is embodied comprises a frame 1, cylinders 2 carried in horizontal position at one end portion of the frame as the rear end portion, the cylinders being arranged in horizontal position lengthwise of the frame, pistons 3 movable in the cylinders and connected to the reciprocating members 4 movable under the front part of the machine, the pistons being shown as provided with piston rods 5 which are connected to carriages 7 movable along guides and forming part of the members 4, and to which rubbers 8 are connected by universal joints. These carriages and rubbers may be of any suitable form, size and construction, as shown in my patent referred to. The carriages 7 are movable along suitable guides or ways 9, Figs. 4 and 6 which are shown as having lengthwise grooves in their side edges in which slide flanges 10 provided on the carriages 7.

During the reciprocation of the pistons which reciprocate oppositely to each other, the members 7 are moved therewith along the guides 9. The pistons are actuated by any suitable motive fluid as compressed air and the flow of the fluid is automatically controlled or timed by a valve 11 and valve gear to be presently described. This valve may be of any suitable form, size and construction and includes an oscillating valve or distribution piece 12, Fig. 7, mounted on a vertical shaft 13 and having ports 14, 15 movable into and out of registration with ports 16, 17, 18 in the head of the valve casting, which communicate with the inlet and exhaust pipes 19. These pipes 19 may be arranged in any suitable manner to lead the compressed air alternately into cylinders and to permit the cylinders to exhaust at their opposite ends in alternation with each other.

It is thought that further description is unnecessary.

The valve piece 12 is oscillated by means of a rocking part 20 mounted on the lower end of the shaft 13 and having arms extending in opposite directions therefrom into the path of shoulders 21 on the carriages 7 respectively.

110 The synchronizing mechanism, that is, the mechanism for holding the pistons 2 or the

members 4 in synchrony with each other, or in juxtaposition, as here shown, includes rotatable elements as worms 22 journaled in the frame above the piston rods and extending through threaded passages 23 in arms 24 rising from the carriages 7. The upper ends of these arms terminate in the shoulders 21. Means is provided for transmitting the motion of one worm 22 to the other, this means consisting of gears 25, see Fig. 5 mounted on the front ends of the worms 22 within the casing or recess at the front end of the frame, and an idler 26 interposed between the gears 25. The recess in which the gears are located is covered by a plate 27.

In operation, during the reciprocating of the members 4 by the pistons 3, said members impart a rotary movement to the worms, and as these worms are connected together one member 4 cannot move ahead or lag behind the other and hence the shoulders 21 engage the rocking part 20 of the valve to reverse the valve at exactly the proper moment with respect to the position of the pistons in the cylinders.

The flow of compressed air from the source of supply to the valve 11 is controlled by a manually operated valve 28 movable in a casing 29 against the spring 30, the valve 28 being operated by suitable means as a lever 31 pivoted to the frame 1 and operated by a grip lever 32 located near the handle 33 of the frame 1.

In addition to the handle 33 which is located at the rear end of the frame, the frame is also provided with a handle 34 at the front end thereof. The frame is also provided with a foot 35 at its rear end as in my patent referred to.

In operation, the operator upon moving the grip lever 32 permits the air to flow through the inlet 36 past the valve 28 and through the outlet pipe 37 into the valve casing 11 and then the flow is controlled automatically by the valve piece or distributor 12.

During the reciprocation of the pistons the pistons and the rubbing members are held in juxtaposition so that the valve is accurately timed by means of the worms 22 and the gearing connecting them.

What I claim is:

1. The combination with oppositely movable reciprocating members, means for actuating said members comprising pistons, cylinders in which the pistons are movable, said members being connected to the pistons respectively, and a valve for controlling the flow of motive fluid to the cylinders, of means movable with said members for controlling the operation of the valve comprising rotatable worms, connected together whereby the motion of one worm is transmitted to the other, the reciprocating members having parts movable along the worms

respectively during the reciprocation of said members to impart rotary movement to the worms, substantially as and for the purpose described.

2. The combination with oppositely movable reciprocating members, means for actuating said members comprising pistons, cylinders in which the pistons are movable, said members being connected to the pistons respectively, and a valve for controlling the flow of motive fluid to the cylinders; of a rocking part for operating the valve, and a pair of rotatable worms connected together whereby the rotary motion of one worm is transferred to the other, said members having parts coacting with and movable along the worms respectively to impart a rotary movement thereto, and also having parts movable alternately into engagement with the rocking part on opposite sides of its axis, substantially as and for the purpose specified.

3. The combination of a pair of oppositely movable reciprocating members, means for controlling the actuation of said members including a shiftable part, said members having means for alternately engaging said part and shifting it first in one direction and then in the other, synchronizing mechanism between said members including a pair of rotatable elements coacting with the reciprocating members respectively to receive movement therefrom, and means for transferring the motion of one element to the other, substantially as and for the purpose set forth.

4. The combination of a pair of opposite movable reciprocating members, means for controlling the actuation of said members including a shiftable part, said members having means for alternately engaging said part and shifting it first in one direction and then in the other, synchronizing mechanism between said members including a pair of rotatable worms, said members having threaded passages coacting with the worms respectively to impart a rotary movement thereto during the reciprocation of said members, and means for transmitting the motion of one worm to the other, substantially as and for the purpose described.

5. The combination of a frame, a pair of parallel cylinders supported by the frame at one end thereof and extending lengthwise of the frame, pistons movable in the cylinders and having rods extending toward the other end of the frame, oppositely movable reciprocating members connected to the rods to be moved thereby, said members being movable under the front end of the frame, an automatic valve for controlling the flow of the fluid to the cylinders, said valve being mounted on the frame between the ends thereof and including an oscillating valve

piece, oppositely extending rock arms connected to the valve piece to oscillate the same, said members having shoulders movable into engagement with the rock arms respectively, worms journaled in the frame above the piston rods, said members being provided with threaded passages coacting with the worms for imparting a rotary movement to the worms during the recipro-

cation thereof, and means for transmitting the movement of one worm to the other, substantially as and for the purpose described.

In testimony whereof, I have hereunto signed my name, at Syracuse, in the county of Onondaga, and State of New York, this 15 1st day of October, 1919.

SPENCER K. BROWN.
